CLAIM

We claim the ornamental design for an artwork wall mount assembly, as shown and described.

DESCRIPTION

FIG. 1 is a front view for an artwork attachment portion of the design;

FIG. 2 is a rear view of the artwork attachment portion of FIG. 1;

FIG. 3 is a perspective view of the artwork attachment portion of FIG. 1;

FIG. 4 is a top side view of the artwork attachment portion of FIG. 1;

FIG. 5 is a left side view of the artwork attachment portion of FIG. 1;

FIG. 6 is a bottom side view of the artwork attachment portion of FIG. 1;

FIG. 7 is a right side view of the artwork attachment portion of FIG. 1;

FIG. 8 is a front view for a wall attachment portion of the design;

FIG. 9 is a rear view of the wall attachment portion of FIG. 8;

FIG. 10 is a perspective view of the wall attachment portion of FIG. 8;

FIG. 11 is a top side view of the wall attachment portion of FIG. 8;

FIG. 12 is a left side view of the wall attachment portion of FIG. 8;

FIG. 13 is a bottom side view of the wall attachment portion of FIG. 8;

(Continued)

FIG. 14 is a right side view of the wall attachment portion of FIG. 8;
FIG. 15 is a front view of an assembled artwork wall-mount that includes both the artwork attachment portion and the wall attachment portion;
FIG. 16 is a rear view of the assembled artwork wall-mount of FIG. 15;
FIG. 17 is a perspective view of the assembled artwork wall-mount of FIG. 15;
FIG. 18 is a top side view of the assembled artwork wall-mount of FIG. 15;
FIG. 19 is a left side view of the assembled artwork wall-mount of FIG. 15;
FIG. 20 is a bottom side view of the assembled artwork wall-mount of FIG. 15;
FIG. 21 is a right side view of the assembled artwork wall-mount of FIG. 15;
FIG. 22 is a front view of an unassembled artwork wall-mount that includes both the artwork attachment portion and the wall attachment portion including directional arrows indicating the direction of assembly which would position the two portions as shown in FIG. 15;
FIG. 23 is a rear view of the unassembled artwork wall-mount of FIG. 22 including directional arrows indicating the direction of assembly which would position the two portions as shown in FIG. 16;

FIG. 24 is a front perspective view of the assembled artwork wall-mount of FIG. 22 including directional arrows indicating the direction of assembly which would position the two portions as shown in FIG. 17;
FIG. 25 is a rear perspective view of the unassembled artwork wall-mount of FIG. 22 including directional arrows indicating the direction of assembly which would position the two portions as shown in FIG. 17;
FIG. 26 is a top side view of the unassembled artwork wall-mount of FIG. 22;
FIG. 27 is a left side view of the unassembled artwork wall-mount of FIG. 22 including directional arrows indicating the direction of assembly which would position the two portions as shown in FIG. 19;
FIG. 28 is a bottom side view of the unassembled artwork wall-mount of FIG. 22; and,
FIG. 29 is a right side view of the unassembled artwork wall-mount of FIG. 22 including directional arrows indicating the direction of assembly which would position the two portions as shown in FIG. 21.
The broken lines in the drawings illustrate portions of the artwork wall mount assembly which form no part of the claimed design.
